UNITED STATES PATENT OFFICE.

NICHOLAS JENKINS, OF WATERBURY, CONNECTICUT, ASSIGNOR TO HOLMES, BOOTH & HAYDENS, OF NEW YORK, N. Y.

SHADE-SUPPORT.

SPECIFICATION forming part of Letters Patent No. 443,525, dated December 30, 1890.

Application filed April 15, 1889. Serial No. 307,228. (No model.)

To all whom it may concern:

Be it known that I, NICHOLAS JENKINS, of Waterbury, in the county of New Haven and State of Connecticut, have invented a certain 5 new and useful Improvement in Shade-Supports, of which the following is a specification.

My improvement relates to those shade-holders which are composed of arms supporting horizontally-extending rings or partial rings by which a shade is sustained.

The object of my improvement is to provide between the arms and the rings or partial rings an engagement which shall be simple 15 and inexpensive and withal effective in precluding any oscillation between the connected parts.

I will describe an arm and shade-ring or partial shade-ring embodying my improvement, and then point out the novel features in the claims.

In the accompanying drawings, Figure 1 is a side view of an arm and a partial ring connected together according to my improvement. Fig. 2 is a view of the reverse side of these two parts. Fig. 3 is a top view of the two parts. Fig. 4 is an edge view. Fig. 5 is a horizontal section taken as indicated by the dotted line $\alpha\alpha$, Fig. 1. Fig. 6 is a side view 30 of an arm and a portion of a ring connected according to my improvement.

Similar letters of reference designate corresponding parts in all the figures.

A designates an arm. It is shown as consisting of a strip of metal—such, for instance, as brass. There may be any number of these arms. It will suffice to use two arranged opposite to each other. These arms may extend from any part commonly used upon or with 40 a lamp or lamp-fixture. It will be seen that the strip is crimped. This serves as ornamentation, and also materially stiffens it in the direction of its narrowest dimension when flat.

The arm A has secured at its upper end a plate B, which may be made of sheet metal. This plate extends horizontally. As here shown, it is bent to embrace the side edges of the arm, and is fastened thereto by rivets 45 passing through it and the arm. Thus a very firm engagement between it and the arm is

secured and its oscillation relatively to the arm precluded.

C designates what I term a "partial ring." It consists of a strip of metal bent into the 55 arc of a circle and having its end portions twisted and bent so as to extend downwardly at right angles and at the extremities bent inwardly and upwardly to form hooks. The lower edge of a shade can rest in the seats 60 formed by the bottoms of the hooks. I have indicated this by representing a portion of a shade in dotted outline. This partial ring C is arranged close to the inner side of the upper portion of the arm A. A screw D passes 65 from it through the arm A and also through the plate B. This screw serves to secure the parts together. As here shown, the screw is affixed to the partial ring and outside the plate B has a nut E applied to it. The plate 70 B has formed upon it prongs b, that extend inwardly through holes c in the partial ring C. The screw D prevents the disengagement of the prongs from the partial ring and the prongs preclude any relative oscillation between 75 the partial ring and the arm.

It will be seen that by my improvement I provide a very simple and efficient connection between a partial ring and an arm.

I have also illustrated in Fig. 5 that the arm 80 A, provided with a plate B, made with prongs b, can be secured to a complete ring C'.

What I claim as my invention, and desire to secure by Letters Patent, is—

1. The combination, with an arm, of a ring 85 or partial ring, a plate embracing the arm and having prongs extending through holes in the ring or partial ring, and a screw passing from the ring or partial ring through the arm and plate, serving to hold the parts together, substantially as specified.

2. In a shade-support, the combination, with a partial ring bent inwardly and upwardly at the extremities, of an arm, a plate secured to the arm and having prongs engaging through 95 holes in the partial ring, and a screw passing from the ring and securing the parts together, substantially as specified.

NICHOLAS JENKINS.
